[57] CLAIM

The ornamental design for a light fixture, substantially
as shown and described.

DESCRIPTION

FIG. 1 is a front perspective view of a light fixture
showing my new design;

FIG. 2 is a top plan view thereof on an enlarged scale;
FIG. 3 is a frontal elevational view thereof on an en-
larged scale;

FIG. 4 is an elevational view on an enlarged scale taken
from the right of FIG. 3;

FIG. 5 is an elevational view on an enlarged scale taken
from the left of FIG. 3;

FIG. 6 is a rear elevational view thereof on an enlarged
scale;

FIG. 7 is a bottom plan view thereof on an enlarged
scale; and

The chain is shown in broken lines of FIG. 1 for illustra-
tive purposes only.
